UNITED STATES PATENT OFFICE.

WILLIAM J. MACFARLAND, OF BOSTON, MASSACHUSETTS.

METHOD OF MAKING SHOES.

1,101,748.

Specification of Letters Patent. Patented June 30, 1914.

Application filed November 28, 1913. Serial No. 803,621.

To all whom it may concern:

Be it known that I, WILLIAM J. MACFARLAND, a citizen of the United States of America, and a resident of Boston, in the county of Suffolk and State of Massachusetts, have invented certain new and useful Improvements in Methods of Making Shoes, of which the following is a specification.

This invention relates to methods of making boots and shoes whereby a shoe may be constructed having great flexibility at the shank and in which an arch support is provided without the use of the metal shank stiffeners in present use.

15 The object of the invention is to provide a means for making shoes which will conform to the anatomy of the foot and will support the weight of the wearer on the bones and cushions of the foot intended by nature to 20 sustain such weight.

25 The invention consists in certain novel means for making shoes having the characteristics desired, all as will be fully understood by reference to the description of the drawings and to the claims hereinafter given.

Of the drawings: Figure 1 represents an elevation of a shoe manufactured by the improved method of the present invention. 30 Fig. 2 represents an inverted plan of the same. Fig. 3 represents an inverted plan of the same, before the outer sole has been secured thereto. Fig. 4 represents a transverse section through the shank of the shoe 35 (without the outer sole) the cutting plane being on line 4-4 on Fig. 3. Fig. 5 represents a transverse section through the front portion of the shoe with the outer sole applied thereto, the cutting plane being on line 5-5 on Figs. 1 and 2. Fig. 6 represents a plan of the upper pattern used in 40 the construction of the shoe. Fig. 7 represents a plan of the inner sole. Fig. 8 represents a plan of the outer sole. Figs. 9 and 45 10 represent respectively sections through the shanks of the inner sole and outer sole after being distorted as secured to the shoe. Fig. 11 represents an elevation of the outer side of a last used in the manufacture of 50 said shoe. Fig. 12 represents an elevation of the inner side of said last. Fig. 13 represents an inverted plan of said last, and Figs. 14 and 15 represent respectively transverse

sections thereof, the cutting plane being on lines 14-14 and 15-15 on Fig. 12 of the drawings.

Similar characters designate like parts throughout the several figures of the drawings.

In the drawings, 10 is the upper pattern 60 cut in the form shown in full lines in Fig. 6, with the corner 11 thrown over toward the center line α α of said upper, this corner 11 being on the inner side of said upper. By cutting the upper pattern in this form 65 and then drawing the corner 11 outwardly into the position shown in dotted lines at 12 on said Fig. 6 and uniting the edges 13 a fullness is created on the inside of the upper opposite the hollow in the shank of the last 70 14 on which it is designed to construct the shoe. The fullness in the upper may be varied by varying the position of the corner 11 relative to the line α α in the formation of the pattern, it being obvious that the 75 nearer the corner 11 is to said center line in the blank as originally formed the more it will be distorted when the edges 13 are united. The corner 11 of the inner side of the upper is thrown in toward the center 80 line α α more than the corner 11^x of the other side an amount equal to the depth of the hollow in the shank of the last, this depth being determined by applying a straight edge 100 to the last as shown in 85 Fig. 13 and measuring the depth of the hollow with a scale 101, this measurement being taken from said straight edge to the line 102 which corresponds to the outline of the inner sole to be used. 90

To the inner side of the upper 10 and opposite the shank, a strip 15 is secured by means of a row of stitches 16. This strip 15 preferably extends beyond the edge of the upper 10 and forms an extension 17 therefor. The outer edge of said extension is provided with one or more incisions 18, preferably two, as shown in Fig. 6 with the inner ends rounded as indicated at 19. The outer edge of this extension 17 is curved as 95 shown at 20 in said figure, this curvature corresponding to the curvature of the rib of the inner sole to which it is to be attached. 100

The last 14 is what is known as a crooked 105 last and the inside of the shank 140 is hol-

lowed more than is usual in lasts now in use. An inner sole 21 is cut in the form shown in Fig. 7, with the heel portion at one side of the position it is intended to occupy in the shoe, this distance corresponding to the depth of the hollow of the last 14 as obtained by the scale 101. This inner sole is provided with a rib 22 shown in full lines in Fig. 3, in dotted lines in Fig. 7, and in section in Figs. 4, 5, and 9. The rib 22 extends from a point 23 in advance of the shank on the inner side around the toe to the point 24 where the shank connects with the heel seat. It will be observed the inner side of the shank thereof is provided with no rib 22.

During the construction of the shoe the inner sole 21 is placed on the bottom of the last 14 and the forward portion is tacked to the fore part of the last. The heel portion is then thrown over into the position shown in dotted lines which will cause the inner side of the shank to be sprung, and a fullness created which is worked down into the hollow of the shank of the last, thereby creating a high arch support at the shank and on the inner side thereof. To facilitate this springing of the inner sole the outer face thereof is chamfered off at the shank from the channel 25 to the inner edge 26 where the material is almost a feather edge as indicated in Fig. 9. The upper is then placed in position on the last and drawn over the edge of the inner sole as indicated in Figs. 3, 4, and 5, and then the various parts of the extension 17 are drawn over the shank and tacked to the last in contact with the outer face of the inside sole. The central part of the extension 17 is drawn direct and the outer parts are drawn in opposite directions toward the heel and toe as indicated in Fig. 3. When the extension 17 has been secured in this manner the strip 15 will extend outwardly along the inside of the shank as shown in Fig. 4. A welt 27 is then placed in position on the last extending from the front of the strip 15 around the toe to the heel seat at 24 and is secured by stitches to the upper 10 and to the rib 22 of the inner sole 21, the same stitches that secure the welt 27 to the rib 22 along the outside of the shank preferably securing the edge 20 of the extension 17 to the said rib 22, all as shown in Figs. 3 and 4 of the drawings, although it is obvious that the edge 20 may be secured independently to the inner sole 21 if desired. The heel portion of the upper 10 is tacked to the inner sole in the usual manner as indicated at 28 in Fig. 3. The welt 27 and edges of the upper 10 having been beaten down and trimmed, a thickness of canvas 29 or similar material is secured to the outer face of the fore part of the inner sole and the shoe is then ready for the application of the outer sole 30 thereto, it being observed

that the inner end of the welt 27 is in continuation of the end of the strip 15 and may or may not be glued thereto as desired. Preferably the abutting ends of the welt 27 and strip 15 are chamfered off and glued together as shown at 150 in Fig. 1. The outer sole 30 is cut in the form shown in Fig. 8, with the heel part at one side of the position it is intended to assume in the shoe, this distance corresponding to the depth of the hollow of the last as obtained by the scale 102. The fore part 31 is tacked to the last in proper position and then the heel portion is moved over into the position shown in dotted lines and is tacked to the last, this forcing of the heel portion laterally relatively to the fore part 31 causing a fullness to be formed on the inner side of the shank at 33 which is worked down into the hollow of the last and forms a high arched support. The inner face of the outside is chamfered off or thinned at the inside of the shank to facilitate the buckling thereof, all as shown at the right of Fig. 10. The partially completed shoe is then taken to a sewing machine and the outer sole 30 is secured to the welt 27 and the strip 15. The corner 141 of the heel seat of the last is curved upwardly as indicated in Fig. 12 and the heel of the shoe is built up at this point in order to throw the weight onto the outside edge of the shoe.

During the manufacture of the shoe the counter stiffener 34 is inserted, this stiffener being of peculiar construction to adapt it to the shoe herein described. It will be observed by reference to Figs. 1 and 2 that while the outer part of the stiffener extends a considerable distance beyond the front of the heel as at 35, the inner side only extends to the front of the heel as at 36, thereby leaving the inside of the shank perfectly free to bend either laterally or vertically. It will be observed that in this construction there is no connection on the inside of the shank between the inner sole and the outer sole, the latter at this point being secured only to the strip 15 which in turn is fastened to the upper 10. This makes this portion of the manufactured shoe very flexible so that it can freely conform to all movements of the foot.

It is apparent that the inside of the shank is provided with several means of supporting the arch. In the first place by means of the fullness in the inside of the upper 10 due to the peculiar shape of its pattern which fullness is drawn in under the arch in the instep by means of the extension 17 and secured in proper position to the opposite side of the shoe, a support for the arch of the foot is created in the nature of a bandage which while yielding sustains the arch of the foot and prevents it breaking down. The arch of the foot is further supported by the raised portion on the inside of

the shank of the inner sole 21 and the similar raised portion on the inside of the shank of the outer sole 30. In fact the arch of the foot is provided with a triple support which has great flexibility and is adapted to yield either laterally or vertically to conform to all movements of the foot.

When completed the shoe corresponds to the anatomy of the foot and provides a support for the arch and all portions of the foot intended by nature to be raised, and causing the weight of the wearer to be sustained by the bones and cushions of the foot. On the outside of the shank it is down low so as to give ample room for the bones and cushions in that part of the foot and a portion of the weight is sustained thereby as well as by the heel and fore part.

It is a well-known fact that the foot of a person in walking or running has an inside tread for the reason that the big toe is the last part of the foot to leave the ground, thereby tending to throw the heel outwardly and giving what is termed an inside or partly rotary tread. This causes all the strain to be thrown on the inside shank of the shoe and usually this is one of the first places to give out in an ordinary shoe. To obviate this breaking of the shoe manufacturers generally drive several nails through the shoe at this point to prevent the breaking of the stitches. As a consequence of this all shoes made on ordinary lasts, whether welted, nailed, pegged, or sewed, in which the outer sole is fastened to the inner sole from the outside heel seat around the last to the inside heel seat are "locked straight" and are so unyielding that they do not conform to the movements of the foot. By constructing the shoe as has been herein described, an "unlocked" shoe is produced having a flexible shank which permits the shoe to fit the foot like a glove and conform to all of its movements.

It must be understood that the arches of the feet of different persons vary considerably in height, and as a consequence in the manufacture of the shoe this fact must be given due consideration, and the upper pattern and the soles of the shoes are thrown off to a greater or less degree in accordance with the arch support wanted in the shoe.

The extension 17 may be formed a part of the upper 10 and the strip 15 be narrower if desired without affecting the principles of the present invention.

Where attempts have been made previously to obtain a flexible shoe it has been necessary to pull the last 14 and then "stab-stitch" the outer sole to the upper by hand. This is a costly procedure and is obviated in the present shoe by the use of the strip 15 which, being sewed to the upper before it is attached to the shoe, provides a means whereby the outsole may be secured to the

inner shank side of the upper by machine and without the removal of the last.

When the fullness has been created in the inner and outer soles to form arches on the inside of the shank it will be impossible to break down these arch supports on account of the shorter distance between the ball of the shoe and its heel than the corresponding points on the soles.

The shoe as manufactured is so flexible that it will yield sidewise and lengthwise and in walking or running the person wearing the shoe will throw the strain, as previously stated, to the inside shank, thus causing the shank to pump up at every step rather than to break down as is usual in ordinary shoes. This upward movement of the inner shank affords a support for the arch of the foot when it is most needed. The shoe when completed may be worn without laces, buttons, or fasteners of any kind, and will not slip at the heel. This result has never been accomplished heretofore as far as is known.

In the manufacture of the shoe it is essential that a last 14 of peculiar construction be used and one that corresponds with the anatomy of the foot.

By reference to Fig. 11 of the drawings it will be observed that all that portion of the bottom of the last outside the central line y—y of the heel is comparatively flat throughout its length, thereby providing ample room in the completed shoe for the bones and cushions of the foot, while the inside of the foot portion of the last is provided at 40 with a projection which will form a depression in the inner sole 21 to accommodate the ball of the foot.

The inside of the shank of the last is hollowed out to a greater degree than is customary in lasts now used, thereby forming a high arch 41 gradually curving upwardly and inwardly from the outer shank 42, which is practically in alignment with the heel and fore part. The last used has a wider tread at the bottom than that of ordinary lasts in order to properly distribute the weight of the body from the heel along the outside of the foot where the bones and cushions lie and then across the ball of the foot to the big toe. At the same time a very high arch is created in the completed shoe which will accommodate the bandage arch support 17 and the bridge supports created by the fullness 43 in the inner sole 21 and the fullness 44 in the outer sole 30, these various yielding supports effectually preventing "flat feet" and in fact assisting in restoring broken arches to their normal condition.

It is believed that the improved method of manufacturing shoes and the many advantages thereof will be fully understood without further description.

Having thus described my invention, I claim:

1. The method of making shoes consisting of attaching a strip to the upper along the inner side of the shank by a row of stitches extending only through said strip and upper, attaching a welt to the upper and inner sole from said strip around the toe to the heel by a row of stitches extending through the welt, 10 upper, and inner sole, and securing an outer sole to said welt and strip.
2. The method of making shoes consisting of providing the inner side of the upper with an extension, drawing said extension over the inner sole and securing its outer edge to said inner sole, said extension having an outwardly extending strip along the inner side of the shank, attaching a welt to the upper and inner sole from the inner front of the shank to the heel on the outer side, and then securing an outer sole to said welt and strip.
3. The method of making shoes consisting of providing the inner side of the upper with an extension having a plurality of ends, drawing the various ends of said extension over the inner sole in different directions and securing their outer edges to said inner sole, said extension having an outwardly extending strip along the inner side of the shank, attaching a welt to the upper and inner sole from the inner front of the shank to the heel on the outer side, and then securing an outer sole to said welt and strip.
4. The method of making shoes consisting of tacking the fore part of an insole to the last and then moving the heel part of the insole laterally toward the inner edge to distort it and form an arch at the shank, tacking said heel part of the insole to the last while thus distorted, attaching a welt to the insole and upper from the heel on the outer side to the shank on the inner side, and then securing the outsole to said welt.
5. The method of making shoes consisting of tacking the fore part of an insole to the last and then moving the heel part of the insole laterally toward the inner edge to distort it and form an arch at the shank, tacking said heel part of the insole to the last while thus distorted, attaching a welt to the insole and upper from the heel on the outer side to the shank on the inner side, attaching a strip to the upper along the inside of the shank, tacking the fore part of an outsole to the last, and then moving the heel part thereof laterally toward the inner edge to distort it and form an arch at the shank, 70 tacking said heel part to the last, and then stitching said outsole to said welt and strip.
6. The method of making shoes consisting of so forming an upper pattern that when its rear ends are connected a fullness will be created in its inner side, attaching a strip to said upper on the inner side thereof, inserting within said upper an inner sole having a high spring arch on its inner side, securing the inner edge of the shank portion 80 of the upper to the outer side of said inner sole, securing a welt to the upper and insole from the end of said strip around the fore part to the outer heel seat, and attaching to said strip and welt an outer sole previously 95 distorted to form a spring arch support on its inner shank.
7. The method of making shoes consisting in taking a last conforming to the anatomy of the foot, measuring the depth of the highest part of the arch thereof on the inside shank, forming an upper pattern with its inner side positioned nearer the center line thereof than the outer side of said upper an amount equal to the depth of said arch of 95 the last, uniting the rear ends of said upper, forming an inner sole with its heel to one side of the fore part a distance equal to the depth of said arch, tacking the fore part to the last, springing inwardly the heel part a 100 distance equal to the depth of said arch, tacking it to the last, securing a welt to the upper and insole from the front end of said strip around the toe to the outer heel seat, forming an outsole with its heel part to one 105 side of the fore part a distance equal to the depth of the arch of the last, tacking the fore part to the last, springing inwardly the heel part and tacking it to the last, working down the fullness thus created into the hollow of the arch on the inner side of the shank, and then securing the outer sole to the welt and said strip.
8. The method of making shoes consisting of tacking the fore part of an insole to the last, measuring the depth of the highest part of the arch on the inside shank, forming an upper pattern with its inner side positioned nearer the center line thereof than the outer side of said upper an amount equal to the depth of said arch of 95 the last, uniting the rear ends of said upper, forming an inner sole with its heel to one side of the fore part a distance equal to the depth of the arch of the last, tacking the fore part to the last, springing inwardly the heel part a 100 distance equal to the depth of said arch, tacking it to the last, securing a welt to the upper and insole from the front end of said strip around the toe to the outer heel seat, forming an outsole with its heel part to one 105 side of the fore part a distance equal to the depth of the arch of the last, tacking the fore part to the last, springing inwardly the heel part and tacking it to the last, working down the fullness thus created into the hollow of the arch on the inner side of the shank, and then securing the outer sole to the welt and said strip.

Signed by me at 4 Post Office Sq., Boston, Mass., this 26th day of November, 1913.

WILLIAM J. MACFARLAND.
